UNITED STATES PATENT OFFICE

2,563,366

COUPLING DEVICE

Henri Raymond, Guissalles by Vindelle, France

Application February 25, 1948, Serial No. 10,844
In France March 27, 1947

3 Claims. (Cl. 285—120)

1

In the closure of bottles and flasks in particular those used for containing drugs and the like, covers or caps are used which are generally formed of plastic material and which are adapted to seal the mouth of the bottle through the compression of a rubber or an agglomerated cork disk. Moreover such caps are formed with an inner screw-thread adapted to engage a complementary thread formed around the upper portion of the bottle neck.

However a large number of bottles or flasks do not comprise such a screw-thread and the top of the neck terminates in an outer flange or shoulder portion. The means used so far for obtaining a tight seal for such containers generally make use of a cork stopper or the like retained in place with string, wire or similar means.

An object of my present invention is to provide a coupling device whereby screw-threaded caps may be mounted on bottles, flasks or other containers of any type. It is further applicable in other connections as in the coupling of two pipe elements for example.

Other objects and features of the invention will appear from the ensuing disclosure made in reference to the accompanying drawing wherein:

Fig. 1 is a vertical cross-sectional view of a coupling device according to my invention, as applied to the closure of a bottle, the cross-section being made on line I—I of Fig. 2.

Fig. 2 is a view in horizontal cross-section on line II—II of Fig. 1.

Fig. 3 is a view in axial cross-section on line III—III of Fig. 4, showing a device according to the invention as applied to the joining of two pipes.

Fig. 4 is a view in transverse cross-section on the line IV—IV of Fig. 3.

In the exemplary embodiment of my invention as shown in Fig. 1, the device is mounted on the neck of a bottle 1. The top of the neck is formed with an outwardly projecting flange or shoulder 2 the under face of which is adapted to abut an outwardly screw-threaded ring formed of two parts 3 and 4 separable lengthwise thereof. Said parts 3 and 4 are connected and held in such condition by means of two lugs 5 and 6 adapted to be gripped when mounting the device.

The threaded ring in this position is ready to receive thereon a cap 7 inwardly screw-threaded so as to engage said threaded ring. Said cap carries a rubber or agglomerated cork disk 8 applied against the inner end wall of the cap (Fig. 1).

The outer portion of the cap is formed with 55 been given merely by way of example. Without

2

castellations 9 to facilitate an efficient clamping engagement thereof around the threaded ring (Fig. 2).

To mount the device on a bottle, the user maintains both parts 3 and 4 of the threaded ring applied against the neck of the bottle 1 by means of the lugs 5 and 6, the ring being positioned against the under face of the shoulder 2 of the neck. It then only remains to screw the cap 7 provided with its cork-disk onto the threaded portion of the ring so as to obtain a tight and perfectly safe seal.

The closure device thus produced forms a unitary assembly adapted to be quickly and cheaply manufactured to provide solid and rugged units adapted to be delivered for sale as easily as the ordinary threaded caps.

Moreover, with range of gauges progressively varied according to the size of the screw threads 20 and the diameter of the bottlenecks, it will be possible to provide a closure for flasks and bottles of all sizes and even certain types of jars.

The use of a sufficiently resilient plastic material such as Celluloid makes it possible to produce a unitary ring member which will simply be slotted along one side thereof so as to enable it to be distended as required.

My device has the further advantage of being adapted to replace the various strap closure means 30 used so far for preserves in bottles or jars.

In the further use of my invention illustrated in Figs. 3 and 4, two tubes 10 and 11, threaded (not necessarily with a common pitch) at their ends, are connected together through the device which 35 herein comprises a nut ring member separated in two parts 12 and 13. Said nut ring member is bored at its upper end to the diameter of the tubes to be joined. The inner recess is provided with a screw thread 14 on which is engageable 40 the pipe 11, the top of said ring engaging the shoulder formed by the thread of the pipe 10 or alternatively a groove formed on assembly by means of a suitable tool. A seal 15 is interposed between the pipes to ensure a tight seal after 45 the ring is clamped thereon. The parts 12 and 13 are strongly pressed against each other by means of a clamp or collar 16 housed under the castellations 17 of the ring so as to be prevented from sliding, and said collar being secured to said ring by means of a bolt 18 which is adapted to strongly clasp the collar only after the ring 50 has been completely screwed onto the pipe 11.

The invention is not limited to the forms of embodiment described and illustrated which have

exceeding the scope of the invention, various modifications may be made in the details thereof. Thus in the pipe 10 of Fig. 3, the inner flange of the ring 12-13 could be made to engage a shoulder formed in any suitable way of the pipe 10. The lugs 6 in Fig. 1 or castellations 17 in Figs. 3 and 4 could be replaced by projecting elements of any suitable form adapted to make it easier during assembly to hold both parts comprising the connecting ring 3, 4 or 12, 13.

What I claim is:

1. A coupling device for coupling two pipe elements a first one of said pipe elements having an external screw thread at the coupling end thereof and the other element having a peripheral radial projection adjacent the coupling end thereof, comprising a ring member internally threaded throughout a portion of its length and adapted to threadedly engage said screw-thread of said first element, an internally projecting flange in 20 said ring formed at the end thereof opposite from said threaded end, said ring being divided throughout its length into two separable parts adapted to join on a diametric plane with said internal flange applied against said outward flange of said second pipe element, and means 25 for clamping said parts of said ring against each other.

2. A coupling device for two pipe elements as claimed in claim 1 wherein said parts comprising said ring member are provided with castellations whereby they may be manually maintained during assembly with a clamping collar located under said castellations.

3. A coupling device for two pipe elements as in claim 1 wherein said peripheral shoulder comprises a screw-thread formed on said other pipe element similar to said screw-thread formed on said first mentioned pipe element.

HENRI RAYMOND.
